(57) **CLAIM**

The ornamental design for a massaging cane device, as shown and described.

DESCRIPTION

FIG. 1 is a front perspective view of the massaging cane device;

FIG. 2 is a front plan view thereof;

FIG. 3 is a back plan view thereof;

FIG. 4 is a first side elevational view thereof;

FIG. 5 is a second side elevational view thereof;

FIG. 6 is a top elevational view thereof; and,

FIG. 7 is a bottom elevational view thereof.

The thin solid lines in the views have been provided for the purpose of illustrating the uniformity of the planar surfaces and the contour of the surfaces and are not a claimed surface pattern.

The broken lines shown in the figures are for the purpose of illustrating portions of the massaging cane device, which form no part of the claimed design.
